(57) **CLAIM**

What is claimed is the ornamental design for an intelligent spraying apparatus, as shown and described.

DESCRIPTION

FIG. 1 is a perspective view showing the intelligent spraying apparatus of Applicant's new design.

FIG. 2 is a left side elevation view of the intelligent spraying apparatus of FIG. 1.

FIG. 3 is a right side elevation view of the intelligent spraying apparatus of FIG. 1.

FIG. 4 is a front elevation view of the intelligent spraying apparatus of FIG. 1.

FIG. 5 is a rear elevation view of the intelligent spraying apparatus of FIG. 1.

FIG. 6 is a top plan view of the intelligent spraying apparatus of FIG. 1; and,

FIG. 7 is a bottom view of the intelligent spraying apparatus of FIG. 1.

The broken lines in the drawings illustrate portions of the intelligent spraying apparatus which form no part of the claimed design.
